UNITED STATES PATENT OFFICE.

ROLLAND S. TROTT, OF DENVER, COLORADO.

GASOLENE ROCK-DRILL.

1,286,152.

Specification of Letters Patent. Patented Nov. 26, 1918.

Application filed April 25, 1917. Serial No. 164,488.

To all whom it may concern:

Be it known that I, ROLLAND S. TROTT, a citizen of the United States, residing at Denver, State of Colorado, have invented 5 certain new and useful Improvements in Gasolene Rock-Drills, of which the following is a specification.

The first object of the invention is to provide a gasolene rock drill which, because of 10 its design will not receive the enormous shocks sustained by other such drills, and will therefore be more reliable and less subject to breakage.

A further object is to provide means 15 whereby the troubles due to the rear air cushion between the fixed stroke piston and the floating piston, (which in Trott, 915,320, Mar. 16th, '09, and in Scott, 1,058,268, April 8th, 1913, must bear the force of the explosion as well as the force of cushioning the 20 return of the fixed stroke piston against the floating piston), will be overcome.

A further object is to provide means whereby a greater number of blows may be struck 25 per minute, through the reduction in reciprocating weight.

A further object is through providing means for more blows per minute, to thereby give less time for each blow and hence less 30 time for air cushion leakage, so that more perfect and reliable cushioning may be obtained with the same clearances between parts.

A further object is to provide means 35 whereby the piston which acts as the hammer may be made in one piece, thereby overcoming the various troubles brought on by built-up hammers.

A further object is to provide a construction 40 whereby the compression space for the explosive gas in the cylinder above the piston is constant and this regardless of the cushioning means between the fixed stroke piston and the floating piston, whereby constant conditions for the operation of the gas engine part of the drill may be obtained.

A further object is to provide means 45 whereby the piston which acts as the hammer may be made much lighter than is possible with the required strength in either the Trott or the Scott constructions mentioned above.

A further object is to provide means so

that a light weight hammer by striking more blows may do as much or more drilling than 55 a heavier hammer striking fewer blows.

A further object is to provide means whereby with more blows per minute, less time for cushion leakage, and lighter reciprocating weights, the internal shocks to the 60 drill will not only be less, but they will be more perfectly cushioned in addition.

A further object is to provide means whereby because of the very long cross-head furnished by the fixed stroke piston, and because the blow-striking can have no rotative effect upon it, no piston pin guides are required, thus allowing for a light rolling or rotative movement of the fixed stroke piston should any such be necessary in order to 70 overcome any small inequalities of stroke or alinement of the two cranks, or any misalinement due to faulty machine work or wear.

A further object is to provide means 75 whereby the slots in the external piston, a source of great weakness in the design, may be done away with, thus allowing equal strength with a much lighter external piston, which means lighter reciprocating 80 weight.

In the drawings, Figure 1. is a section on a vertical longitudinal plane; and Fig. 2. is a top elevation with partial section.

In Fig. 1 it will be seen that the water 85 jacketed cylinder 1, is provided with exhaust ports 2 and by-pass ports 3, a mixing valve 4, spark plug 5 and spark timer 6, all substantially the same as in the ordinary two cycle engine. 90

The cylinder, 1, has slots, 7, in its walls, through which the piston pin, 8, of the fixed stroke piston, 9, protrudes.

The fixed stroke piston, 9, is equipped with the usual baffle plate, 9^a, for the upward deflection of the incoming charge, and is of exceptional length, though hollow and light.

The holes, 9^b, allow the mixture to be compressed into and exhausted out of the hollow, 9^c, of the piston, 9, on each revolution, thus forming a positive means of cooling both the head of the piston, 9, and the rear cushion of the hammer, 14.

Connecting rods, 10, connect the piston 105 pin, 8, with the cranks, 11, of the crank-

shaft, 12. The hammer block, 13, fits slidingly but closely in a bore in the front end of the cylinder, preventing any leakage of charge at that point.

- 5 The construction thus far described will run as an ordinary two cycle engine; it is entirely independent of the striking mechanism as far as running is concerned. The fixed stroke piston, 9, by its direct connection with the crankshaft, 12, will leave exactly the same compression space in the cylinder on each backward stroke; and the explosive force will all be directly expended upon moving forward the fixed stroke piston, 9, and the shaft, 12, without any intermediate cushioning, and its attendant troubles.

Because of this constant compression space, and the constant relation between the 20 explosion and the crankshaft, the engine will run steadily, and its running will be in no way affected by the efficiency of the cushioning of the drilling part of the construction.

- 25 The floating piston or hammer, 14, is located partly inside and partly outside of the fixed stroke piston, 9, the hammer flange, 14^a, fitting slidingly but closely in the bore, 9^a, of the piston, 9, and the hammer bar, 14^b, fitting slidingly but closely through the header, 15, and extending forward outside of the piston, 9.

It will be seen that because of this construction, the hammer flange, 14^a, has an air 35 cushion on either side of it.

The small holes, 16, through the walls of the piston, 9, are to allow part of the explosive mixture to enter the hollow, 9^a, on either side of the hammer flange, 14^a, and 40 act as an air cushion, as a cooling means, and at the same time to lubricate the surfaces with oil that is drawn into the engine with the charge.

The rotation shaft, 17, is revolved from 45 the crankshaft, 12, by means of two sprockets and a chain, 18; and its worm, 17^a, meshing with the gear, 19, on the chuck, 20, revolves the chuck, and thus the drill steel, 20^a.

50 The spark timer, 6, is mounted on the rotation shaft, 17, and is to be connected by the usual batteries, coil, and wire to give a properly timed spark at the spark plug, 5.

It will be seen that upon each backward 55 stroke (see arrow B) of the fixed stroke piston, 9, the gas in the cylinder is compressed, the spark explodes the charge, and the piston, 9, is driven forward, revolving the shaft, 12, by means of the rods, 10; the 60 exhaust passes out of the ports, 2, and the fresh charge which has been compressed in front of the piston, 9, by its forward stroke, sweeps in through the by-pass ports, 3, and is directed up into the cylinder by the baffle 65 plate, 9^a, on the head of the piston, 9. The

inertia of the flywheels, 21, acting through the rods, 10, now returns the piston, 9, on the next back stroke, this acting to suck in the next fresh charge through the mixing valve, 4; the compressed charge in the cylinder is then fired by the spark, driving the piston, 9, forward, and so on.

When the piston, 9, stops at the end of the back stroke, the hammer, 14, continues on backward, compressing the gas back of 75 it into a cushion. When the pressure of this cushion gets great enough the backward movement of the hammer, 14, is stopped.

When the hammer, 14, is in this backward position, the forward set of holes, 16, will 80 be uncovered, and the space in front of the hammer flange, 14^a, and inside of the piston, 9, will be filled with gas. As the piston, 9, now travels forward the hammer, 14, will move forward also, impelled by the highly 85 compressed cushion behind it. When the piston, 9, reaches the end of its forward stroke, the hammer, 14, will continue on forward till it strikes the hammer block, 13, against which the drill steel is pressed. Thus 90 the blow that does the drilling is struck.

On this further independent forward stroke of the hammer, 14, it compresses the gas in front of the flange, 14^a, against the header, 15, which is mounted in the front 95 end of the piston, 9, and when the piston, 9, moves on its next backward stroke this pressure is increased till it is great enough to move the hammer, 14, backward. When the hammer, 14, is in this forward position, 100 the backward set of holes, 16, through the walls of the piston, 9, will be uncovered and gas will be forced into the piston, 9, back of the hammer flange, 14^a.

Thus it will be seen that in my improved 105 drill a small one-piece hammer may be used, which means three or four pounds of weight instead of the ten or twelve pounds required when the hammer is external and has to be slotted. This light hammer, besides having no weak spots due to slots, will put comparatively little strain on the cushions; the higher speed allowed by the reduction in reciprocating weight will maintain the cushioning more perfectly with the same 115 clearances between parts; and since the force of a blow varies with the square of the striking velocity of the hammer, the lighter hammer at higher speed will strike as hard as the heavier slower hammer. It will also be 120 seen that the force of the explosion is not transmitted to the shaft through any cushion, which always means trouble with the cushion, but is transmitted direct, through the external piston and the rods, to the 125 shaft. It will also be seen that the cushions are cooled and oiled positively by the mixture and the oil drawn in with it, and that the heat of the explosion is prevented from being carried to the cushions from the ex- 130

ternal piston head by means of a positively cooled intermediate insulating space in the external piston.

It should be noted that the cushion back 5 of the hammer flange, 14^a, must stop the backward travel of the hammer, 14, unassisted; while the cushion in front of the flange, 14^a, as a general thing is required only to cushion the return of the piston, 9, 10 against it, as the drill steel, 20^a, through the hammer block, 13, is what does most of the stopping of the forward movement of the hammer, 14. It will be seen that the area 15 of the cushion back of the hammer flange, 14^a, is greater than that in front of it by an amount equal to the area of the hammer bar, 14^b. Also, the gas that feeds the cushion back of the flange, 14^a, is under compression due to the forward stroke of the 20 piston, 9; while the gas that feeds the cushion in front of the flange, 14^a, is somewhat rarefied because of the suction on the mixing valve; this difference between the compression and the suction tends to help the 25 difference in areas of the two cushions in making the backward cushion much stronger than the forward cushion, as it should be.

This not only gives a better cushion on 30 the back stroke, where it is needed, but a freer blow at the end of the forward stroke, which is desired.

It will be seen that the exact timing and the proportions of these various operations 35 mentioned above, will vary according to a good many factors, such as, weight of the hammer, 14; position, number, and size of the holes, 16; amount of compression space in front of the piston, 9; number of blows 40 per minute; length of cushions on each side of the hammer flange, 14^a; length of hammer bar, 14^b; length of hammer block, 13, and its position as determined at will by the drill operator, etc.

45 Therefore, I do not wish to confine my construction to any one set of conditions or proportions, out of the many under which my invention will satisfactorily operate; but what I claim, is:—

50 1. In an explosive engine, the combination of a two cycle ported cylinder having a combustion chamber, a hollow piston within the cylinder, a partition dividing said piston into two chambers, a floating piston 55 partly within the chamber farthest from the combustion chamber and adapted to operate a drilling device, a shaft, and means for operating the shaft connected to the hollow piston adjacent the partition.

60 2. The combination of a hollow piston divided into two chambers by a partition, a floating hammer piston partly within one of said chambers, and a piston pin adjacent the partition of the hollow piston.

65 3. In an internal combustion rock drilling

engine, the combination of a cylinder ported for intake and by-pass of explosive mixture and exhaust of spent gases, an external fixed stroke piston divided into two chambers by a partition, a floating piston operating 70 partly within the forward chamber of the said fixed stroke piston, said pistons being moved in each forward stroke by the explosion and expansion of gas within the cylinder, and a crankshaft connected with the 75 fixed stroke piston adjacent the partition and operable to move the pistons on the rearward stroke.

4. In an explosive engine of the character described, the combination of a cylinder, a 80 fixed stroke piston divided by a partition into two chambers, a floating piston partly therein, said pistons having differential movement, said cylinder being adapted for the explosion of gas therein to move said 85 pistons on each forward stroke, means for providing cushions between said pistons, a shaft connected to the fixed stroke piston adjacent the partition and rotated by the fixed stroke piston on the forward movement of the pistons and operating to return the pistons on the rearward stroke, and means for controlling the admission and exhaust of gas to and from the cylinder.

5. In an explosive engine of the character 95 described, the combination of a two cycle ported cylinder, an external fixed stroke piston divided by a partition into two chambers and a partly inclosed floating piston in one of said chambers with which the 100 floating piston co-operates, a shaft connected to the external piston adjacent the partition, and means operated by the shaft for rotating said drilling device.

6. In an explosive engine of the character 105 described, the combination of a two cycle ported cylinder, an external fixed stroke piston divided by a partition into two chambers, and a partly inclosed floating piston in one of said chambers with which the floating piston co-operates, a shaft connected to the external piston adjacent the partition, a 110 drill which is designed to be struck with the hammer block, and means operated by the shaft for rotating said drill.

7. In an internal combustion percussive engine of the character described, the combination with a drilling device of a two cycle ported and slotted cylinder, an external fixed stroke piston divided by a partition into two chambers, a floating piston arranged partly within said external piston and adapted to deliver impact upon the drilling device, a pin carried by said external piston adjacent the partition and having its ends projecting through said cylinder slots, a shaft, and connections between said pin and shaft for driving the latter.

8. In an explosive engine of the character 125

described, the combination of a two cycle ported cylinder, a drilling device mounted at one end of the cylinder, two pistons mounted within the cylinder, one of said 5 pistons being divided by a partition into two chambers, one of said pistons being arranged partly within the other, one of said pistons being in the nature of a floating piston and designed to operate the drilling 10 device, the other of said pistons having a fixed stroke, a crankshaft operated by the last mentioned piston and adapted to move said pistons away from the drilling device, and means for providing cushions between 15 said pistons.

9. In an explosive engine of the character described, the combination of a slotted cylinder, a drilling device mounted in one end of said cylinder, two pistons arranged with- 20 in the cylinder, one of said pistons being partly contained by the other, one of said pistons being in the nature of a floating piston adapted to strike the drilling device, and the other of said pistons having a fixed 25 stroke and being divided by a partition into two chambers, a crankshaft adapted to receive energy from said pistons on each for-ward stroke for the purpose of moving them on their rearward stroke, and a pin carried 30 by said fixed stroke piston adjacent said partition and projecting through the slotted cylinder and connected to said shaft to operate same.

10. In a percussion engine of the charac-

ter described, the combination of a two cycle 35 ported cylinder having an explosion chamber and a charge receiving chamber, means for introducing an explosive fluid into the charge receiving chamber and transmitting said fluid to said explosion chamber, two 40 pistons arranged within the cylinder, one of said pistons being mounted partly within the other, said pistons having relatively dif- 45 ferential movement, one of said pistons being in the nature of a floating piston and adapted to deliver impact, and the other having a fixed stroke and being divided by a partition into two chambers, a drilling de- 50 vice for receiving a blow from the floating piston, and a crankshaft operated by the 55 fixed stroke piston for moving the pistons on the rearward stroke.

11. In a percussive engine of the character described, in combination, a two cycle ported cylinder provided with an explosion 60 chamber and a charge receiving chamber, said chambers being provided with means for communication whereby a charge may be conveyed from the latter to the former, an external fixed stroke piston divided by a 65 partition into two chambers within said cylinder, a floating piston adapted to move with the said fixed stroke piston and to deliver blows, and a crankshaft operatively connected with said fixed stroke piston whereby said pistons are returned on their rearward stroke.

ROLLAND S. TROTT.
